MULTIPLE PURPOSE CLOTHESPIN

Ernest Allred, San Francisco, Calif., assignor of forty-nine per cent to Theodore W. Jett, Oakland, Calif.

Application March 1, 1944, Serial No. 524,606

1 Claim. (Cl. 24—139.1)

This invention relates to a multiple purpose clothes-pin of a so-called three-in-one type, that is, a unitary structure embodying a pair of parallel selectively and individually usable clothespins and an intervening complementary part which serves to permanently attach the unitary structure to the line to thus render it susceptible of expedient use and to avoid loss of the device.

Although the structure is susceptible of manufacture from wood and other materials it is preferably fashioned from a single length of wire of proper gauge, this being bent intermediate its ends and at its end portions to define the main triple-part assembly and a stabilizing and reinforcing horizontal frame-work.

Other features and advantages will become more readily apparent from the following description and the accompanying illustrative drawings.

In the drawings, wherein like numerals are employed to designate like parts throughout the views:

Figure 1 is an elevational view showing a pair of the so-called multiple purpose clothes-pins in use and illustrating how they may be conveniently employed to suspend articles from a clothesline.

Figure 2 is a perspective view which satisfactorily portrays, it is believed, the formation of the overall structure and the designing and relationship of the component parts.

Figure 3 is a side elevational view of the structure showing the grips or clamps detached from the line with the suspension loop on the line to retain the device on the line when not in use.

Referring now to the drawings by distinguishing reference numerals, the unitary structure comprises what may be identified as four main phases or components, namely, the duplicate longitudinally spaced clothes-pins or clamps A and B, the intervening line attaching member C and the horizontal and embracing and stabilizing frame-work D.

As before indicated, the device is preferably constructed from a single length of wire of appropriate resiliency and gauge. The length of wire is bent centrally to form the part C which is an elongated loop 4 to surround the clothesline L. The loop-ends are twisted together as at 5 and diverge in opposite horizontal directions to form limbs 6. From this point on the clothespins A and B are fashioned as is likewise the so-called frame-work D. As each pin is the same in construction a description of one will suffice for both, the same reference characters

are used to identify identical parts. Following this theme the free end of the wire is bent down at right angles in parallelism to the loop 4 as indicated at the point 7 and is then formed with a series of coating bends to define a pair of parallel resilient grips or jaws 8 and an upstanding central stem portion terminating in an elevated finger-grip 9. Then the wire is bent in a horizontal direction to form an adapter loop 10 which surrounds the median portion of the clothes-pin and the terminal end is twisted around the corresponding opposite end as indicated at 11, the final end terminating as at the point 12. The manner in which the wire-ends 15 are bent as at the point 13 just before reaching the twist 11 permits the two portions 6 and 13 to form somewhat triangular members adjoining the loop 10. These triangular members afford the desired rigidity to the complete structure and the loops 10 prevent undue spreading and reinforce the coating portions of the respective clothes-pins A and B.

In practice the devices are placed on the clothesline L to function as shown to better advantage in Figure 1. Here it will be observed that the opposite ends of the articles are suspended on the line, the articles being indicated at 14, that is to say, the two clothes pins at the opposite ends of each device engage adjacent 20 ends of the respective articles 14. There is sufficient resiliency in the gripping jaws of the pins to permit them to be individually snapped down over the line to clamp the article as shown. The finger-pieces 9 rising above the structure facilitate the operation above and the sustaining or suspension loop 4 serves to retain the device on the line at all times and in readiness for use.

It is thought that persons skilled in the art to which the invention relates will be able to obtain 40 a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

50 A multiple purpose clothespin construction of the class described, comprising a single length of resilient wire bent upon itself at its center to define an elongated line-attaching loop; said loop being closed by a twist of the wire, the end portions then being bent at right angles in opposite

directions, looped upwardly to form finger grips, and thence into W-shape to form a pair of longitudinally spaced parallel, double-jaw clothespins, the central upward loop of the W-shaped portions extending above the upper extremities thereof to provide finger pieces, said ends being extended transversely across the inner sides of said W-shaped portions and thence looped to form finger grips at the opposite side of the pins from said first-mentioned finger grips, and then extended transversely across the outer sides of

said W-shaped portions in parallel relation to the portions extending across the inner sides thereof to provide means for maintaining the vertical alignment of said W-shaped portions, the said ends being then returned to a point centrally positioned over said line-attaching loop, and clinched by twisting the opposite ends together, thus forming a longitudinal reinforcing portion.
